APPARATUS FOR TREATING PARAFFIN

Lewis H. Macomber, Kalamazoo, Mich.

Application August 4, 1930. Serial No. 472,997

10 Claims. (Cl. 100—50)

The main objects of this invention are:

First, to provide an apparatus for treating paraffin by the cold press process, to facilitate the removal of oils and soft or amorphous waxes.

Second, to provide an apparatus for this purpose which is of large capacity and very substantially reduces labor and waste incident to methods now commonly employed for the purpose.

Third, to provide an apparatus having these advantages which occupies comparatively little space, notwithstanding that it is of large capacity.

Objects pertaining to details and economies of my invention will definitely appear from the description to follow. The invention is defined in the claims.

A structure embodying the features of my invention is clearly illustrated in the accompanying drawing, in which:

Fig. 1 is a fragmentary sectional view of an apparatus embodying the features of my invention.

Fig. 2 is a horizontal section on line 2—2 of Fig. 1.

Fig. 3 is an enlarged fragmentary view in vertical section on line 3—3 of Fig. 1.

The embodiment of my invention illustrated comprises a vertically disposed cylindrical filter chamber 1 having a foraminous wall portion 2. This foraminous wall portion extends in practice a substantial portion of the length of the chamber. The filter chamber preferably has a comparatively slight upward taper, the purpose of which will appear as the description proceeds.

This filter chamber is mounted on a supporting frame 3, and projects through the deck or floor 4. The filter chamber of the commercial embodiment of my invention, from which this drawing was prepared, is about fourteen feet in length.

At its lower end the filter chamber is provided with a discharge head or gate 5 of the full area of the chamber which is clamped in its closed position by a plurality of hinged bolts 6 pivoted at 7 on the flange 8 at the lower end of the filter chamber. The gate has radial notches 9 adapted to receive the bolts which are provided with clamping nuts 10. In order that the gate may swing clear to permit discharging the load, I provide a projecting hinge arm 11 having an inclined slot 111 therein which is engaged by pin 112 on the hinge arm 113 on the gate. This allows the gate to move vertically into clamping engagement with the gasket 114 on the lower end of the filter chamber. To assist in closing the gate I provide a winch 115 for the cable 116 connected to the gate opposite its hinge.

The filter chamber is provided with a flange 12 at its upper end internally shouldered to receive the clamping ring, the clamping member being firmly clamped by means of screws 117. The filter chamber has a similar shoulder 118 at its lower end to receive the lower end of the fabric and is clamped within this shoulder by the ring 119 and screws 117, the purpose being to hold the fabric or lining securely in position and prevent the wrinkling or the displacement.

The filter chamber is surrounded by a drain jacket 16 which terminates short of its lower end so as not to obstruct the manipulation of the gate. This drain jacket is disposed concentrically relative to the filter chamber and is provided with a discharge pipe 17 at its lower end.

I preferably provide a heating coil 18 within the lower end of the drain chamber, the purpose of which is to prevent solidifying of the oils and soft or amorphous waxes which are discharged by the means hereafter described. The steam is supplied to the coil 18 by means of the pipes 19 and 20, the pipe 19 being valved and connected to the steam pipe 21. This pipe 21 is connected to the drain jacket by means of the valved pipe 22 so that, if desired, steam may be admitted to the drain jacket to free the wax from the walls thereof and facilitate its discharge through the gate.

The plunger cylinder 23 is of substantially the same diameter as the upper end of the filter chamber and is mounted thereon constituting an extension therefor. This plunger cylinder has a valved charging connection 24 through which the wax to be treated in a semi-solid state may be forced under pressure. The downward stroke of the plunger 25 is limited by the stop 26 positioned above the charging connection 24.

The plunger is provided with an annular groove 27 which may be engaged by the locking screw 95 or detent 28 adapted to hold the plunger in its upper or fully retracted position.

To indicate the position of the plunger I preferably provide an indicator 29 connected by the cable 30 to the plunger. This cable runs through a curved guide 31 on the upper end of the cylinder.

The actuating fluid such as air under pressure is admitted to the cylinder at its upper end through the pipe 32 and at its lower end through the pipe 33, which pipes are connected to the supply pipe 34 through the three-way valve 35. The wax to be treated, however, may be and preferably is employed for returning the plunger to its retracted position, so it would only be neces-

sary to employ the actuating fluid connection 32. While I have for convenience illustrated the steam pipe as opening to the jacket at only three points, it should be pointed out that in practice it is desirable to admit steam at several uniformly-spaced points about the jacket so that there is a uniform heating.

In operation the paraffin wax to be treated for the removal of oils and soft amorphous waxes is heated and ligroin or petroleum ethers in suitable quantities added thereto. After thoroughly mixing the mixture is cooled preferably by being subjected to a refrigerating machine or apparatus, and when in a crystalline condition is forced into the filtering apparatus through the connection 24. When fully charged the plunger is actuated under high pressure which forces the solvent oils and amorphous waxes from the paraffin body into the filter or drain chamber. It is very important to secure the best results that the pressing operation occur when the wax is in a crystalline condition, and it is very desirable to use a refrigerating means for cooling, as the cooling of a large mass can be more readily accomplished and controlled.

The heating coil in the bottom of the drain chamber does not materially raise the temperature of the wax which is being treated, but prevents clogging of the lower part of the drain chamber by solidifying of the waxes therein.

After the oil charged solvent has been forced from the body of the wax being treated, the discharge gate is opened and steam is admitted to the drain chamber, which will slightly warm or melt the surface of the body of wax so that it is freed from the walls of the filter chamber. Owing to these walls being downwardly-expanded, the treated mass is quickly discharged by air pressure admitted in front of the piston through the cock 35. This makes possible a very rapid operation of the device, which is not only of large capacity but very efficient in the removal of objectionable matter.

While the apparatus illustrated is designed for treating paraffin wax, it may be adapted for treatment of other materials. I have not illustrated or described such embodiments, as it is believed this disclosure will enable those skilled in the art to embody or adapt my improvements as may be desired.

Having thus described my invention what I claim as new and desire to secure by Letters Patent is:

1. In an apparatus of the class described, the combination of a vertically disposed cylindrical foraminated filter chamber provided with a discharge gate at its lower end, said chamber being expanded downwardly, said gate being of the full area of the chamber, a tubular fabric lining for said filter chamber disposed in supporting engagement with the wall thereof and secured at its upper end to the filter chamber wall, a concentrically disposed drain jacket surrounding said filter chamber and terminating above its said gate, said drain jacket having a discharge at its lower end, heating means disposed within said drain jacket adjacent its lower end, a valved means for supplying a heating medium to said drain jacket, a vertically disposed plunger cylinder of substantially the same diameter as said filter chamber opening to the upper end thereof, a valved charging connection to the lower end of said plunger cylinder, a plunger within said cylinder, and connections for supplying plunger actuating fluid to said plunger cylinder.

2. In an apparatus of the class described, the combination of a vertically disposed cylindrical foraminated filter chamber provided with a discharge gate at its lower end, a fabric lining for said filter chamber disposed in supporting engagement with the wall thereof, a concentrically disposed drain jacket surrounding said filter chamber and terminating above its said gate, said drain jacket having a discharge at its lower end, heating means disposed within said drain jacket adjacent its lower end, means for supplying a heating medium to said drain jacket, a vertically disposed plunger cylinder of substantially the same diameter as said filter chamber opening to the upper end thereof, a valved charging connection to the lower end of said plunger cylinder, a plunger within said cylinder, and connections for supplying plunger actuating fluid to said plunger cylinder.

3. In an apparatus of the class described, the combination of a vertically disposed foraminated filter chamber provided with a discharge gate at its lower end, a fabric lining for said filter chamber, a drain jacket surrounding said filter chamber and terminating above its said gate, heating means disposed within said drain jacket, a valved means for supplying a heating medium to said drain jacket, a vertically disposed plunger cylinder opening to the upper end of said filter chamber, a valved charging connection to the lower end of said plunger cylinder, a plunger within said cylinder, and connections for supplying plunger actuating fluid to said plunger cylinder.

4. In an apparatus of the class described, the combination of a filter chamber having foraminated walls and provided with a discharge gate at one end, a drain jacket surrounding said filter chamber, means for supplying heat to said filter chamber, a fabric lining for said filter chamber, a plunger cylinder opening to said filter chamber, a charging connection opening to said plunger cylinder adjacent said filter chamber, and a plunger within said plunger cylinder.

5. In an apparatus of the class described, the combination of a filter chamber having foraminated walls and provided with a discharge gate at one end of the full area of the cylinder, said filter chamber having a relatively slight taper from its discharge gate, a fabric lining for said filter chamber, a plunger cylinder opening to said filter chamber and of a diameter substantially the same as that of the filter chamber, a charging connection opening to said plunger cylinder adjacent said filter chamber, and a plunger within said plunger cylinder.

6. In an apparatus for treating paraffin of the class described, the combination of a filter chamber having foraminated walls and provided with a discharge gate at one end, a drain jacket surrounding said filter chamber, a fabric lining for said filter chamber, a plunger cylinder opening to said filter chamber, a charging connection opening to said plunger cylinder adjacent said filter chamber, and a plunger within said plunger cylinder.

7. In an apparatus of the class described, the combination of a filter chamber tapered toward one end and having a foraminated wall and provided with a discharge gate at its larger end, a fabric lining for the said foraminated wall, a plunger cylinder opening to the smaller end of said filter chamber, a plunger within said plunger cylinder, means for supplying actuating fluid to said plunger cylinder, a charging connection

in communication with the smaller end of said filter chamber and with said plunger cylinder beyond the in-stroke of the plunger whereby the material to be filtered may be employed to re-
5 turn the plunger, and a drain jacket for the foraminous portion of the walls of said filter chamber and constituting a heating fluid chamber.

8. In an apparatus of the class described, the combination of a filter chamber tapered toward one end and having a foraminous wall and provided with a discharge gate at its larger end, a fabric lining for the said foraminous wall, a plunger cylinder opening to the smaller end of said filter chamber, a plunger within said plunger cylinder, means for supplying actuating fluid to said plunger cylinder, and a charging connection in communication with the smaller end of said filter chamber and with said plunger cylinder beyond the in-stroke of the plunger whereby the material to be filtered may be employed to return the plunger.

9. In an apparatus for treating paraffin of the class described, the combination of a conical filter chamber having a foraminous wall and provided with a discharge gate at the larger end, a fabric lining for the foraminous wall, a plunger cylinder opening to the smaller end of said filter chamber, a plunger within said plunger cylinder, means for supplying actuating fluid to said plunger cylinder, a charging connection for said filter chamber, and a drain jacket for the foraminous portion of the walls of said filter chamber and constituting a heating fluid chamber.

10. In an apparatus for treating paraffin of the class described, the combination of a conical filter chamber having a foraminous wall and provided with a discharge gate at the larger end, a fabric lining for the foraminous wall, a plunger cylinder of constant diameter opening to the smaller end of said filter chamber, and a plunger within said plunger cylinder.
